INTERCOMMUNICATION UNIT

Johann Kloss, Vienna, Austria, assignor to International Standard Electric Corporation, a corporation of Delaware

Filed Sept. 5, 1963, Ser. No. 76,562

Claims priority, application France Mar. 7, 1963

Term of patent 14 years

(Cl. D26—14)

The single figure is a perspective view of an intercommunication unit, showing my new design. The essential features of this design are a cuboidal object having sides that are slightly bowed in each of two dimensions, with a front sloping gently from a base section upward a predetermined distance toward pushbuttons mounted on a top section, said top section comprising a relatively wide flange surrounding a trapezoidal inset grill together with an arcuate back surface rising to a height which is slightly greater than the said predetermined distance, all as shown.

The opposite side not shown is substantially a mirror image of the side shown, and the back, not shown is plain and unornamented.

I claim:

The ornamental design for an intercommunication unit, as shown and described.
